Catholina Lambert of New York City, Des 2490
Letters Patent No. 3490. Dated Oct. 9, 1866
Design for Drapery Trimming.

The Schedule referred to in this Letters Patent and making part of the same.

To all whom it may concern:

It is known that I, Catholina Lambert of New York, in the County and State of New York, have originated and designed a new pattern for trimming; of which the following is a full, clear and exact description, referring back to the accompanying specimens or drawings making part of this Specification.

This trimming is made either on the Power, loom or hand loom. A certain number of warps are first stretched, the wefts are then woven between the warp in the Ogee pattern, for one or more shoots when the weft is formed on one side of the warp into a large loose loop, after this the weft is again interwoven with the warp for one or more meshes, and then again in a large loose loop formed, and so on until the whole length of the band or trimming is completed.

The warp for the formation of this description of trimming may consist of twisted, or untwisted material, but the weft must be of untwisted threads of any desired material to give the required appearance to the trimming.

In Figure I, a short piece of the trimming is represented, and in Figure 2, the same is shown in an enlarged view where a, a, a, are the warp threads, and b, the weft, c, represents the Ogee pattern of connecting the weft with the warp, and d, shows the large projecting loop. These loops, when two or more of these trimming bands are secured or attached together, side by side, represent the appearance of hair-curls.

What I claim as my invention and desire to secure by Letters Patent is The Design of the trimming substantially as herein set forth and described

Witnessed (Robert Harnill.
